METHOD AND APPARATUS FOR APPLYING
CAPS TO BOTTLESJohn R. Gammeter, Akron, Ohio, assignor of
one-half to Susan G. Gammeter, Akron, Ohio

Application June 3, 1936, Serial No. 83,286

15 Claims. (Cl. 226—81)

This invention relates to improvements in bottle capping methods and apparatus and more particularly to improvements in the apparatus disclosed in my copending application Serial No. 5 29,693, filed July 3, 1935. The invention is more particularly adapted for applying to milk bottles and the like, caps of the type disclosed in my copending application Serial No. 14,248, filed April 2, 1935.

10 In my aforesaid copending apparatus application I have disclosed a machine in which bottles are adapted to be brought into alignment with a magazine containing a plurality of caps each of which comprises parallel top and bottom portions, the latter having an opening therein to receive a plurality of fingers which grip the bottom portion of the lower cap spreading same into a skirt and placing the cap on a bottle. This machine has worked satisfactorily but it 15 has been found desirable to direct a blast of air into the opening in the cap to assist the fingers to more readily engage the cap, and it is, therefore, an object of this invention to provide means for directing such air blast and to move such 20 means out of the way of the fingers at the appropriate time.

When the caps are made wholly or partly of a film that does not easily stretch, for example, of a rubber hydrohalide film, such as is disclosed 30 in Calvert Patent No. 1,989,632, January 29, 1935, which product is obtainable on the market under the trade name "Pliofilm", it has been found desirable to heat the air directed against the cap so as to render the material more pliable and it 35 is another object of the present invention to provide this heated air.

A further object is to provide means for moving the cap containing magazine a predetermined amount to assist the fingers in gripping the caps, 40 and to generally improve the mechanism disclosed in my prior application.

A further object is to provide a novel method for applying caps to bottles, particularly when such caps are initially in the form of parallel 45 discs having an opening in the lower disc.

Other objects and advantages will become apparent from the following description taken in conjunction with the accompanying drawings.

In the drawings,

50 Figure 1 is a top plan view of the apparatus; Figure 2 is an enlarged bottom plan with parts broken away and shown in section;

Figure 3 is a vertical section taken substantially on line 3—3 of Figure 1 with some parts 55 shown in elevation;

Figure 4 is a section taken substantially on line 4—4 of Figure 3;

Figure 5 is an enlarged detail view of the lower end of the magazine and adjacent parts;

Figure 6 is a vertical section taken substantially on line 6—6 of Figure 1 with some parts shown in elevation; and

Figure 7 is a similar view taken substantially on line 7—7 of Figure 1 with parts broken away.

Referring to the drawings, the numeral 10 designates a base which supports an upright or standard 11 having an integral annular bracket 12 formed at the upper end thereof to receive the upper end of a depending tubular member 13, the lower end of which extends into proximity 15 with the top of a milk bottle 14 or the like. Preferably the bracket 12 is split as at 15 and a bolt 16 is threaded through lugs 17 carried by the bracket on opposite sides of the split whereby tightening of bolt 16 will rigidly secure tube 13 20 within the bracket at any suitable height. If desired, the standard 11 may be made vertically adjustable in accordance with the disclosure in my said copending application. The lower end of tube 13 has an annular cam member 18 arranged thereon, a ring 19 being fitted around the upper portion of the cam member and a screw 20 being threaded through the cam and ring into engagement with the tube substantially as shown in Figure 6, to secure the cam and ring to the 30 tube. A plurality of spaced guides 21 are formed integral with ring 19 and extend above the arcuate surface 22 of the cam member. The foregoing parts of the apparatus are all stationary during the operation thereof.

Slidably mounted on tube 13 below bracket 12 is a sleeve 23, the lower end of which has one end of a plurality of spaced fingers 24 pivotally secured thereto as at 24', which fingers are offset as at 25 to engage the cam surface 22 for actuation thereby. The free ends of fingers 24 are bent substantially into U-shape with the ends 26 disposed adjacent the axis of tube 13 and extending slightly into the tube at the lower end thereof when the fingers are in their upper position shown in full lines in Figures 3 and 6. A spring or elastic band 27 encircles the fingers and tends to maintain them in the position shown in Figure 3. Sleeve 23 and fingers 24 are adapted to be moved from the full line to the broken line position shown in Figure 6. To prevent turning of sleeve 23 on tube 13 a longitudinal slot 26' is provided in the tube to slidably receive a key or projection 27' on the sleeve.

As clearly shown in Figure 4, bracket 12 is 55

provided with spaced openings 28 which slidably receive rods 29 carrying a sleeve 30 at their upper ends. This sleeve (Figures 3 and 6) has an annular seat 31 therein which receives an annular collar 32 that slidably encircles a tubular magazine 33 which extends into tube 13 and terminates a slight distance above the lower end of the latter. The upper end of magazine 33 has an extension 34 press fitted thereon, a flange 35 on said extension being adapted to receive a plurality of bolts 36 which extend into collar 32 and have nuts 37 thereon. The arrangement is such that bolts 36 may be turned to raise and lower the magazine and thus adjust the position of the lower end thereof with respect to the lower end of tube 13. It will be apparent that the magazine may be readily lifted out of tube 13 since it is supported therein by collar 32 which can be lifted from its seat 31. The magazine is adapted to be filled with a plurality of caps 38 which initially have their upper and lower portions 39 and 40 respectively arranged parallel, an opening 41 being provided in the lower portion of each cap, and on the lower end of the magazine is arranged an extension 42 having an inwardly directed flange 43, which flange serves to prevent the caps falling out of the magazine. A longitudinal slot 44 (Figure 3) is provided in the magazine to facilitate filling same with caps, said slot permitting entrance of an object, such as an operator's finger, upon which a stack of caps may be placed, said object and caps being readily lowered into the magazine, as will be understood.

Means are provided for raising and lowering sleeve 23 with its fingers 24, such means also serving to slightly raise and lower the magazine. As shown, the reduced end 45 of a stub shaft 46 is threaded into bracket 12 (Figure 3), and a cam wheel 47 is rotatably mounted on this shaft, 40 said wheel preferably being held in place by a plate or washer 48 having a screw 49 extending through the plate into shaft 46. A cam groove 50 is arranged in wheel 47 and receives a roller 51 rotatably mounted on a stub shaft 52 secured 45 in sleeve 30. Cam wheel 47 has the reduced end 53 of a stub shaft 54 threaded thereinto, said shaft 54 having a handle 55 secured thereon as at 56 and having one end of a crank arm 57 mounted thereon. The other end of crank arm 50 57 is rotatably mounted on a stub shaft 58 having its reduced end 59 threaded into sleeve 23. A plate 60 and screw 61 preferably are utilized to retain arm 57 on shaft 58. It will be noted that by turning handle 55, cam wheel 47 will rotate 55 and due to the peculiar arrangement of cam groove 50 will raise and lower the magazine, and simultaneously, crank arm 57 will raise and lower sleeve 23.

Referring now to Figures 1, 2, 6 and 7, an enlarged portion 62 is provided on standard 11 to receive a unit which directs the passage of air into the lower end of tube 13. This unit is secured to the standard by screws 63 which extend through meeting faces 64 of the unit and standard, said unit having a tube or pipe 65 provided with an air passage 66, the upper end of said pipe being curved as at 67 whereby it will tightly rest against a boss 68 on standard 11 and passage 66 will be aligned with an opening 69 that extends 65 through the boss into a chambered portion 70 of the standard. Passage 66 extends longitudinally through pipe 65 and communicates with a transverse passage 71 formed in a trunnion 72 which is secured in pipe 65 by means of a screw 73. An opening 74 (Figure 7) in the trunnion

communicates with passage 71 and with an opening 75 formed in one end of a lever arm 76 which is pivoted on the trunnion. One end of an arcuate tube 77 is tightly fitted into the opening 75, as by sweating, and the arrangement is such that a continuous passage is provided from chamber 70 to the free end of tube 77. With tube 77 secured to the pivoted end of arm 76 the tube and arm can be swung about trunnion 72 in the manner of a bell crank, and a coil spring 78 is arranged on the annular portion 79 of arm 76 to normally urge said arm and tube 77 toward the broken line position illustrated in Figure 6, the ends of the spring being secured respectively to said arm and pipe 65.

The opposite end of arm 76 is pivoted to the lower end of a vertical rod 80 as at 81, the upper end of said rod having an elongated slot 82 which receives a pin 83 mounted on one end of a lever 84 pivoted as at 85 to the pipe 65. The other end of lever 84 is arranged in the path of travel of an enlarged portion 86 formed on lower end of sleeve 23 whereby movement of lever 84 from the broken to the full line position shown in Figure 6 is accomplished by upward movement of sleeve 23. By virtue of the elongated slot 82 a period of lost motion is provided which will be referred to later. Secured to rod 80 is a projection 87 which extends toward pipe 65 and which is adapted to limit the downward movement of said rod by engagement with a projection 88 on said pipe. A spring 89 is arranged on rod 80 between projection 87 and pin 83 to urge the latter to the upper end of slot 82.

Referring to Figure 7, a pipe 90 is adapted to extend into standard 11 to communicate with chamber 70, which pipe conducts air from a conventional blower or fan 91 into the chamber 70 from which it passes through the unit which directs it into contact with the caps in magazine 33. Under some conditions it is desirable to heat the air and I have shown a conventional heater 92 through which the air is adapted to pass after it leaves the blower 91. When the heater is in operation hot air will be delivered to the caps, but when not in operation the air merely passes through the heater without any substantial change in its temperature. I prefer to have a continuous passage of air through the connection from the blower, but if desirable, a suitable valve (not shown) could be arranged in the air line to provide for intermittent air blasts. The heater is used to heat the air when the caps are made wholly or partly of a film that does not easily stretch, for example, of a rubber hydrohalide film, marketed under the trade name "Pliofilm", since the heat renders such film more pliable and easier to handle.

In operating the apparatus, after magazine 33 has been filled with caps and assuming sleeve 23 and fingers 24 to be in their lowermost position shown in broken lines in Figure 6, handle 55 is turned to rotate cam wheel 47 in the direction indicated by the arrow in Figure 6. Rotation of the cam wheel will move sleeve 23 and fingers 24 to their uppermost position and the cam groove 50 will move roller 51 and consequently magazine 33 a slight distance upwardly. In Figure 5 the relative amount of upward movement of magazine 33 is clearly shown from the broken line to the full line position. It should also be noted that as the fingers 24 extend through opening 41 in the lower cap they raise the entire stack of caps a slight amount. During upward movement of sleeve 23, projection 86 thereon will en-

gage lever 84 causing the latter to push rod 80 downwardly to swing air tube 77 into the full line position shown in Figure 6, where, since the flow of air from blower 91 is continuous, it will direct air against the stack of caps causing separation of the walls of the lower cap substantially as shown in Figures 3, 5 and 6.

In order that air tube 77 will direct air against the caps long enough to insure separation of the walls thereof, and in the event heated air is used to insure provision of sufficient heat before the air tube is retracted, I take advantage of the lost motion slot 82 in the following manner. As rod 80 moves downwardly spring 89 is sufficiently strong to hold pin 83 at the upper end of slot 82 until projection 88 prevents further movement of the rod, at which time air tube 77 will have reached its uppermost position. At this time sleeve 23 can still move upwardly a distance equal to the length of slot 82 and such continued movement of this sleeve causes pin 83 to move to the lower end of slot 82 against the action of spring 89. Therefore, air tube 77 remains in its uppermost position during the time the pin 83 is moving from the top to the bottom of slot 82.

Now, as rotation of the cam wheel continues, sleeve 23, fingers 24 and magazine 33 begin to move downwardly and the fingers will begin to spread by reason of the cam surface 22 engaging the offset portions 25 thereof. At the time the ends 26 of the fingers spread enough to engage the bottom portion 40 of the lower cap by contacting the wall of opening 41, sufficient air will still be directed against the caps to insure separation of the top and bottom portions thereof whereby a positive grip on the cap will be secured by the fingers. The slight downward movement of magazine 33 also permits a better grip of the fingers on the lower cap than if the magazine is allowed to remain stationary. The stack of caps will, of course, move to its lower position as soon as the fingers move out of the magazine. The movement of this stack upwardly has been necessary to provide sufficient room for the separating of the walls of the lower cap and the weight of the stack on the finger ends insures a relatively strong surface for the air to impinge against in separating the walls of the lower cap. As fingers 24 continue their downward movement the lower portion of the lower cap is spread substantially as shown in broken lines in Figure 5 and continued spreading provides an opening sufficient to permit the cap to pass over the top of a bottle 14 where it is placed as shown in Figure 6, the portion 40 which initially was parallel with portion 39 having become a skirt which tightly grips the bottle. While sleeve 23 is moving downwardly the spring 78 is returning rod 80 and lever 84 to their initial position and reTRACTING air tube 77 to the broken line position shown in Figure 6. In the latter position air tube 77 is out of the path of the fingers with its free end extending into the space between two of the fingers, as will be understood. In fact, the position of tube 77 at all times is entirely clear of interference with the fingers.

The apparatus is adapted to be operated continuously by rotation of the handle in one direction only, and a cycle is completed for each bottle capped. As the bottles are placed in position they will be rapidly and efficiently capped.

While I have illustrated and described the preferred steps of my method and the preferred form of apparatus, it will be apparent that the invention is not so limited, and various modifications

may be made within the scope of the subjoined claims.

What is claimed is:

1. The method of capping a bottle with a cap formed of parallel discs having a substantially central opening in one of said discs which comprises directing a current of air into said opening to separate said discs, stretching, while the discs are separated, said disc having said opening therein to increase the size of said opening sufficiently to allow a bottle top to pass therethrough and at the same time forming a skirt out of the latter disc to grip the bottle below the top thereof, and placing said skirt over the top of the bottle.

2. The steps in the method of capping a bottle with a cap formed of parallel discs having a substantially central opening in one of said discs which comprises directing a current of air into said opening to separate said discs, and stretching, while the discs are separated, said disc having said opening therein to increase the size of said opening sufficiently to allow a bottle top to pass therethrough and at the same time forming a skirt out of the latter disc to grip the bottle below the top thereof.

3. In bottle capping apparatus, in combination, a movable cap container, means for withdrawing a cap from said container, a common means for operating said first-named means and for moving said container, and means for directing a current of air into said container during at least a part of the operation of said cap withdrawing means.

4. In bottle capping apparatus, in combination, a movable cap container, means for withdrawing a cap from said container, a common means for operating said first-named means and for moving said container, means for directing a current of air into said container during at least a part of the operation of said cap withdrawing means, and means for moving said air directing means out of the path of travel of said cap withdrawing means.

5. In bottle capping apparatus, in combination, a cap container, means for withdrawing a cap from said container for placement over a bottle, means for directing a current of air against said cap prior to its withdrawal from said container, and means for moving said last named means out of the path of travel of said withdrawing means.

6. In bottle capping apparatus, the combination of a cap container, means for directing a current of air into said container, and means for moving said first-named means into and out of a position where air can be directed into said container.

7. In bottle capping apparatus, the combination of a cap container, means for withdrawing a cap from said container, means for directing a current of air into said container, and means operable by said cap withdrawing means for moving said air directing means into a position where air can be directed into said container.

8. In bottle capping apparatus, the combination of a cap container, means for withdrawing a cap from said container including a sleeve slideable longitudinally of said container, means for directing a current of air into said container, and means operable by sliding said sleeve for moving said air directing means into a position where air can be directed into said container.

9. In bottle capping apparatus, the combination of a cap container, means including a sleeve slideable longitudinally of said container for withdrawing a cap therefrom, means for directing a

- current of air into said container, and a lever arranged in the path of travel of said sleeve and engageable for moving said air directing means into a position where air can be directed into said container.
5. 10. In bottle capping apparatus, the combination of a cap container, means for directing a current of air into said container, means for moving said first named means into and out of a position where air can be directed into said container, and connections providing a predetermined period of lost motion of said first named means.
10. 11. In bottle capping apparatus, the combination of a cap container and means for directing a current of air into said container, said means comprising a tube movable into and out of a position where air can be directed into said container, a lever for moving said tube, and connections between said tube and lever providing a definite period of lost motion of said tube during operation of said lever.
15. 12. In bottle capping apparatus, the combination of a cap container, means for withdrawing a cap from said container, a tube for directing air into said container and movable into and out of a position where air can be directed into said container, and a lever operable by said cap withdrawing means for moving said tube.
20. 13. In bottle capping apparatus, the combination of a cap container, means for withdrawing
- a cap from said container, a tube for directing air into said container and movable into and out of a position where air can be directed into said container, a lever operable by said cap withdrawing means for moving said tube, and connections between said tube and lever providing a predetermined period of lost motion of said tube during operation of said lever.
25. 14. In bottle capping apparatus, in combination, a cylindrical support, a tubular cap containing magazine arranged in said support and movable relatively thereto, a sleeve slidable on said support and carrying fingers for engaging and withdrawing a cap from said magazine, and a common means for sliding said sleeve and moving said magazine while a cap is being withdrawn from the latter.
30. 15. In bottle capping apparatus, in combination, a cylindrical support, a tubular cap containing magazine arranged in said support and movable relatively thereto, a sleeve slidable on said support and carrying fingers for engaging and withdrawing a cap from said magazine, a common means for sliding said sleeve and moving said magazine while a cap is being withdrawn from the latter, and means operable by said sleeve for directing a current of air into said magazine prior to the withdrawal of said cap.

JOHN R. GAMMETER. 30
